UNITED STATES PATENT OFFICE.

HOMER L. McFARLAND, OF CONWAY, MISSOURI.

AIR-COUPLING.

1,259,118.

Specification of Letters Patent. Patented Mar. 12, 1918.

Application filed April 2, 1917. Serial No. 159,268.

To all whom it may concern:

Be it known that I, HOMER L. McFARLAND, a citizen of the United States, residing at Conway, in the county of Laclede 5 and State of Missouri, have invented certain new and useful Improvements in Air-Couplings, of which the following is a specification.

This invention relates to an improved air pipe coupling and the principal object of the invention is to provide a coupling so constructed that it may be mounted beneath the car and connected with the car body the train pipe for carrying the coupler head and 10 connection with the hose of the air system, being slidably connected with the bracket structure which bracket structure is formed in two sections, one being connected with the car and the second pivotally connected with 15 the first section and rigidly connected with 20 the car coupler.

Another object of the invention is to provide an air coupling device having an improved type of bracket structure for connection 25 with the body of the car and improved means for slidably mounting the train pipe and coupler head.

Another object of the invention is to provide an improved type of coupler head, the 30 coupler heads of the adjoining car being duplicates and so constructed that they are slidably connected in overlapping relation and provided with air passages terminating at the sides in seats to receive gaskets meeting 35 to form an air-tight closure between the two coupler heads.

Another object of the invention is to so construct this coupling device that when 40 turning a bend in a road, the inner bracket structure may have pivotal movement necessary but at the same time be yieldably held 45 to extend longitudinally of the car thus returning the structure to its normal position and yieldably holding it in this position when the car is moving along an even section 50 of the track.

This invention is illustrated in the accompanying drawings, wherein:

Figure 1 is a top plan view of the improved train pipe coupling device.

Fig. 2 is a view in side elevation showing the improved coupler device connected with adjoining cars under the car couplers thereof.

Fig. 3 is a horizontal sectional view 55 through the improved coupler.

Fig. 4 is a view in end elevation of one of the coupler heads.

Fig. 5 is a sectional view taken along the line 5—5 of Fig. 2.

Fig. 6 is a fragmentary sectional view 60 through a portion of the device.

This coupler is for connecting the train pipes or air pipes 10 of the adjoining cars 11 which cars are connected by means of the conventional couplers 12 positioned beneath the cars and supported by the brackets 13. The couplers 12 are positioned as shown in Fig. 2 and it will thus be seen that when the cars are brought together and the car couplers 12 connected, the couplers for 70 the air pipes will also be automatically connected thus making it unnecessary for a train-man to walk between the cars in order to connect the air pipes.

The coupling devices at the ends of the 75 car are duplicate in structure and therefore a description of one will suffice for both. Beneath the end of the car there will be provided a bracket structure including an outer 80 bracket 14 and an inner bracket 15, the outer bracket 14 extending transversely of the car and connected with the body of the car by means of bolts or other fasteners 16 and the inner bracket extending longitudinally of the car and provided with upstanding end 85 walls having ears 18 extending therefrom to receive fasteners 19 for connecting the end walls with the side strips 17. From an inspection of Fig. 6, it will be seen that the inner bracket 15 is provided with a tapered 90 opening 20 to receive conical lug 21 of plate 14' rotatably mounting the inner bracket thus permitting the necessary pivotal movement of this inner bracket when the car is turning a curve in the track. A pin 22 extends through this bearing lug 21 and carries a spring 23 to engage the lower face of the outer bracket and yieldably hold the inner bracket in tight engagement with the outer bracket, an abutment washer 24 being 95 mounted upon the upper end of the pin to engage the inner bracket and a securing nut 25 being screwed upon the pin to hold the pin in place. In order to limit the pivotal movement of the inner bracket or carriage 100 as it might be termed, there are provided springs 26 connected with the arms of the outer bracket 24 and with ears or lugs 27.

The coupler head is provided with a body 110 28 having a passage 29 formed therein and

terminating in a side opening 30 having an enlarged outer end portion forming a seat 31 for the gasket 32 which gasket provides an air-tight connection between the couplers 5 of the adjoining cars when brought together. A yoke 33 is connected with the body 28 by arms 34 and is provided with a cutout 35 in which there is positioned a gear wheel or pinion 36 rotatably mounted by means of a bolt or pin 37. This pinion engages the teeth of the rack 38 of an adjoining coupler and serves as means for assisting movement of the couplers into and out of an operative position. Abutments 39 are provided to 10 limit the sliding movement of the couplers toward a connected position and in order to permit the body of each coupler to easily move into the space between the body and the yoke of the adjoining coupler, the outer end portion of the body has been tapered as 15 shown in Figs. 3 and 4.

This coupler head is mounted upon the pipe 40 with which the air-pipe 10 is connected as shown in Fig. 1, the pipes being 20 slidably mounted in openings formed in the end walls 17 of the inner brackets or carriages 15 and a spring 41 being mounted upon the pipe between the coupler head and the wall 17 to yieldably hold the head extended and provide a tight but yielding engagement between the heads of the adjoining couplers when the cars are brought together. Guide rods 42 are slidably carried by the wall 17 of the inner bracket or carriage 25 15 and are connected with the coupler heads and are provided with heads 43 at their free ends which through engagement with the inner wall of the bracket will prevent the spring 41 from moving the coupler head and pipe 40 outwardly beyond a desired amount when the cars are uncoupled.

When in use, the pipe coupler will be connected with the car as shown in Figs. 1 and 2, and from an inspection of these figures, it 30 will be readily seen that the couplers at the ends of the car will be identical in structure and so mounted that when two cars are brought together, the couplers at the adjoining ends of the cars may be brought together thus forming a connection between the air pipes of the two cars. From an inspection of Fig. 3 it will be readily seen that when the two couplers are connected, a very tight joint will be formed preventing leakage of air in the air system of the train. At the same time, the necessary movement is 35 permitted as the train moves over a track, this being especially necessary when a train is moving over a rather rough road bed or along a track containing curves. When the cars of a train are separated, the pinions 36 will be rotated and the coupler heads will thus more easily be separated. This prevents danger of the couplers becoming stuck 40 and broken when the cars are being separated.

As previously explained the rods 42 not only serve as means for aiding in guiding the sliding movement of the pipes 40 and coupler heads but further serve as means for limiting the movement of the pipes and 70 heads in one direction.

What is claimed is:—

1. A train pipe coupler comprising adjoining car elements each having a support comprising an outer bracket, an inner 75 bracket pivotally connected with the outer bracket and means for yieldably holding the inner bracket to extend at substantially right angles to the outer bracket, in combination with a coupler head, an air pipe leading from the coupler head and slidably carried by the inner bracket for connection with a train pipe, resilient means positioned upon the pipes between the coupler head and the inner bracket to yieldably hold the head and pipe against sliding movement in one direction, and guiding rods slidably carried by the inner bracket and connected with the coupler head and provided with enlarged end portions for engaging the inner bracket 80 to limit the sliding movement of the coupler head and pipe in one direction.

2. In an air pipe coupler, coöperating elements for adjoining car ends each element comprising supporting means having a main 95 bracket for connection with a car, a second bracket constituting a carriage and provided with an opening, a bearing lug extending from the main bracket into the opening to pivotally mount the carriage, a pin extending through the bearing and provided with an abutment for engaging the carriage, resilient means engaging the main bracket and pin to yieldably retain the pin in a set position with the abutment in engagement 100 with the carriage, a pipe connected with the carriage, a coupler head connected with the pipe and provided with a passage communicating with the pipe, and resilient means connected with the carriage and with the main bracket to yieldably hold the carriage 105 in a set position.

3. A train pipe coupler comprising coöperating elements for adjoining car ends, each comprising a supporting element including a carriage having upstanding arms, a pipe slidably carried by said arms, a coupler head carried by said pipe and provided with an air passage communicating with the pipe, guide rods slidably carried by the 115 arms of said carriage and connected with the coupler head and provided at their inner ends with abutments for limiting the outward movement of the rods, and resilient means mounted upon the pipe between the 120 coupler heads and carriage, to normally move the coupler heads away from the carriage.

4. A coupler comprising elements for adjoining car ends each having a support in- 130

cluding a carriage, an air pipe carried by said carriage, and a coupler head comprising a body connected with the outer end portion of said pipe and provided with a 5 passage communicating with the pipe, a rack formed upon said body, and a yoke extending from the body for embracing the body of an adjoining coupler when the couplers of two cars are connected, and a pinion rotatably connected with the yoke for engaging the teeth of the rack of the adjoining coupler.

5. A train pipe coupler comprising coupler elements for adjoining car ends, each 15 having supporting means for connection with the car, a coupler head having a body provided with an air passage, a yoke extending from the body and provided with a pocket, a pinion rotatably mounted in the 20 pocket, teeth formed upon the body, the pinion of one coupler head engaging the rack of a coöperating coupler head when the coupler heads are connected with the body of one coupler head embraced by the 25 yoke of the second coupler head, a pipe ex-

tending from the body for communication with the air passage thereof and slidably carried by the support, guide rods slidably carried by the support and connected by the coupler head, and resilient means yieldably assisting movement of the coupler head toward the support. ³⁰

6. A coupler for air pipes comprising couplers for adjoining cars each including a support having a main bracket for connection with the car body and an auxiliary bracket resting upon the main bracket, the auxiliary bracket being pivotally connected with the main bracket, an air pipe movably supported by the auxiliary bracket, a coupler head connected with the air pipe, and means carried by the auxiliary bracket and engaging the coupler head to guide the sliding movement of the coupler head. ³⁵

In testimony whereof I affix my signature ⁴⁰
in presence of two witnesses.
